UNITED STATES PATENT OFFICE.

ALLAN S. BARROWS, OF CHICAGO, ILLINOIS.

SHEET-METAL CAR-DOOR.

1,815,537.

Specification of Letters Patent. Patented Sept. 9, 1919.

Application filed August 10, 1917. Serial No. 185,411.

To all whom it may concern:

Be it known that I, ALLAN S. BARROWS, a citizen of the United States, residing at Chicago, in the county of Cook and State 5 of Illinois, have invented a certain new and useful Improvement in Sheet-Metal Car-Doors, of which the following is a full, clear, concise, and exact description, reference being had to the accompanying drawings, forming a part of this specification.

This invention relates to improvements in sheet metal car doors.

One object of my invention is to provide an all-metal door more particularly adapted 15 for use on railway box cars and having great strength to resist lateral thrusts in proportion to the weight of metal employed.

Another more specific object of my invention is to provide a door of the character 20 above indicated which is adapted to be made from a single sheet of metal and have the edges and body portion thereof strengthened entirely by integral formations.

The invention furthermore consists in the 25 improvements in the parts and devices and in the novel combination of the parts and devices herein shown, described and claimed.

In the drawing forming part of this specification, Figure 1 is a side elevation of a 30 car door showing my improvements. Fig. 2 is a horizontal, sectional view upon a somewhat larger scale, of the structure illustrated in Fig. 1, and taken on the line 2—2 thereof. Fig. 3 is an enlarged vertical, sec- 35 tional view taken substantially on the line 3—3 of Fig. 1, and showing the upper rail structure. Figs. 4 and 5 are enlarged detail sectional views illustrating modifications adapting the door to car construction 40 when it is desirable to form a spark and rain seal. And Fig. 6 represents another embodiment of the invention.

In Fig. 2, parts are broken away to prevent crowding of the drawing.

45 In the construction illustrated in Figs. 1, 2 and 3, the door B is of the usual outside type. As shown, the door B is made of a single sheet of metal and all of the edges thereof are doubled back upon itself, as indicated at 115—115 on the sides, 116 across the top and 117 across the bottom. At the right hand end, as viewed in Figs. 1 and 2, that is, the rear end of the door, the doubled portion of the door edge is shown as bent 50 at right angles to the main portion of the door, as indicated at 50, to thereby form a

stop for engagement with a suitable post or flange on the side of the car. In this construction, the door B is provided around all four edges with an outwardly extended rib 60 or corrugation 151 and the central portion of the door is dished inwardly within the area defined by the ribs or corrugations 151. Said central dished portion is also provided with outwardly extended ribs or corruga- 65 tions 120 and 121 preferably extending horizontally. The ribs 120 terminate within the ribs 151 whereas the ribs 121 are preferably merged therewith at the ends. As most clearly shown in Fig. 2, the doubled- 70 over portions 15 and 115 are preferably ex- tended over the ribs 151—151 and spot welded, as indicated at 215—215. This not only adds strength to the door but serves the additional function of preventing any of the 75 load from lodging within the vertical ribs 151—151 which might prevent opening of the door. As shown in Fig. 3, the doubled-over portions 116 and 117 are preferably ex- tended over the adjacent horizontal ribs 80 151—151 and spot welded, as indicated at 216—216, for the purpose of providing ad- ditional strength, particularly in back of the hanger brackets, hereinafter described. With this construction, it is obvious that the 85 edges of the door are thoroughly reinforced without unduly thickening the door and at the same time great strength is provided to resist torsional effect on the door or lateral blows.

90 Referring to Fig. 3, the method of hang- ing the door is more clearly illustrated. As there shown, 52 represents the roller track and 53 the roller-carrying brackets. The latter are provided with rollers 54 traveling 95 on the track 52. As clearly illustrated in Fig. 3, the upper corrugation or rib 151 of the door is designed to fit the bracket 53, as indicated at 55, the bracket fitting over said rib and being riveted thereto, as indi- 100 cated at 56, and also to the door proper, as indicated at 57. In this connection, it may be stated that the brackets 53 are of a well known form and I have adapted my sheet metal door so as to permit the use of 105 such brackets without modification thereof and, where necessary, permit the reemployment of old brackets. On its rear edge, the door may be provided with short pieces of angle iron, as indicated at 58, to better pro- 110 tect the door when it is moved to fully open position and where it strikes against the

usual door stops. The door can be held in closed position by any suitable means, such as the lock and seal indicated generally by the reference 59 in Fig. 4.

5 In some instances, it is desirable to make a spark and waterproof joint around the door when the latter is in closed position, and in Figs. 4 and 5 modifications to accomplish this result are indicated. In Fig. 4 is shown a horizontal section of the rear edge 10 of the door, said edge being inclined inwardly and toward the forward edge of the door, as indicated at 150 and adapted to engage under a correspondingly formed flange 152, the latter forming either a part of the side door post or being secured thereto. In Fig. 5 is represented the bottom edge of the door, the doubled-over portion 217 being bent at right angles to the main portion of 15 the door and adapted to lie under a floor plate or threshold plate and thus form a seal, as above indicated.

In the construction illustrated in Fig. 6, 20 the strength of the door against lateral thrusts is obtained by dishing the door inwardly with a rectangular panel, as indicated at 60, and within the latter is formed a substantially circular outwardly extending dished portion 61. Centrally of the latter, 25 the door is again dished inwardly with a circular portion, as indicated at 62, the latter being made in the form of a very shallow cone. The edges of the door are formed in the same manner as in the other structures 30 and need not be specifically described. 35 With my invention, the door is made comparatively light yet exceedingly strong; bracing beams such as Z-bars and the like are not required; all riveting may be substantially 40 eliminated if spot welding is employed as described; and the door conforms to present standard railway practice and can be interchanged with old doors or applied to new equipment.

45 I claim:

1. As an article of manufacture, a rectangular door adapted to slide horizontally, 50 said door being composed of sheet metal and provided with edge corrugations therein located relatively close to the edges, said corrugations paralleling respective adjacent edges, the sheet metal being provided also with additional strengthening indentations 55 within the boundaries of said edge corrugations, said door being formed with relatively narrow, plain marginal portions outside of said edge corrugations, said marginal portions being formed of multiple thicknesses of sheet metal lying against each 60 other and rigidly united, all said corrugations and indentations being disposed on one

side of the plane defined by said marginal portions, said corrugations and indentations serving to strengthen the door against lateral, vertical, and torsional strains, one ply 65 of each of said marginal portions being extended over the corresponding adjacent edge corrugation and rigidly secured to the main portion of the door within the boundary of the edge corrugations. 70

2. As an article of manufacture, a door, 75 said door being composed of sheet metal and provided with outwardly extending, hollow edge corrugations disposed adjacent to and paralleling the vertical edges of the door, the door being provided also with additional outwardly extending integral strengthening depressions within the boundaries of the edge corrugations, said door having relatively narrow marginal portions disposed 80 outside of said edge corrugations, said marginal portions being composed of a multiple of plies of sheet metal, the innermost ply of metal, along each vertical edge on the inner 85 side of the door, being extended over and beyond the corresponding adjacent vertical edge corrugation and rigidly united to the main portions of the door within the boundary of the corresponding edge corrugations 90 to thereby brace and cover the latter and prevent articles located on the inner side of the door from lodging in said vertical corrugations when the door is in closed position. 95

3. As an article of manufacture, a door of 100 substantially rectangular form and adapted for use as a box car door, said door being composed of sheet metal and provided with edge corrugations therein located relatively close to each edge and paralleling the latter, the sheet metal of said door being provided also with additional corrugations between the vertical edge corrugations, the door being formed with relatively narrow marginal portions outside of said edge corrugations, said marginal portions being composed of a multiple of plies of sheet metal, one of said plies of metal along each edge of the door being extended over the corresponding adjacent edge corrugation and rigidly 110 secured to the body of the door within the boundary of the edge corrugations to thereby cover the latter and brace the corrugation, the multiple-ply marginal portion along one vertical edge of the door being 115 extended at an angle to the door to thereby form a stop.

In witness that I claim the foregoing I have hereunto subscribed my name this 24th day of July, 1917.

ALLAN S. BARROWS.
